CLAIM

The ornamental design for a shin guard set, as shown and described.

DESCRIPTION

FIG. 1 is a perspective view of a first component of a shin guard set showing my new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second component of the shin guard set shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

(Continued)

FIG. 17 is a perspective view of the shin guard set where the first component of the shin guard set is sleeved on the second component of the shin guard set; and,

FIG. 18 is an exploded perspective view of the shin guard set.
